SHAKER CONVEYER SYSTEM

Ernst R. Bergmann, Chicago, Ill., assignor to
 Goodman Manufacturing Company, Chicago,
 Ill., a corporation of Illinois

Application April 20, 1948, Serial No. 22,224

16 Claims. (Cl. 198—220)

1

This invention relates to improvements in shaker conveyor systems and has principal reference to latching or locking means for ball frames supporting the reciprocating conveyor trough sections of such systems.

Shaker conveyor systems for transporting material in mines generally employ trough sections connected in overlapping or abutting relationship, such connected trough sections being supported for reciprocating movement upon what are commonly termed ball frames. The supporting ball frames each consist of a stationary portion resting on the mine floor, and are generally held firmly in place by jacks or struts which bear against the mine roof, and also of a movable portion to which the trough sections are connected and supported, provision being made in such ball frames for free movement of the movable portion with respect to the stationary portion by means of balls which ride in races or guideways formed in each portion.

Such ball frames of the prior art have been open to the objection that upon removal from such shaker conveyor systems the frames were not stable for convenient handling and oftentimes injuries were caused to workmen. In an effort to prevent such unintended movement of the ball frames, locking pins had sometimes been provided which passed through both portions of the frame. Such pins had, perforce, to be removed when the frame was placed in the shaker conveyor system else damage would be caused to the system by the failure of the ball frame to reciprocate freely. Obviously, such pins were also easily lost or misplaced, thus rendering the ball frames unstable during handling.

With the foregoing considerations in mind it is a principal object of the invention to enable a ball frame for a shaker conveyor to be transported or handled in a locked or stable condition, such a frame being characterized by being immediately ready for reciprocating movement as soon as the shaker trough sections are supported by the frame, such readiness for operation being possible with no necessity for using pins or other locking devices prior to such operation.

Another object is to enable a ball frame for a shaker conveyor to be readily handled in locked condition prior to placing on a mine floor, such locked condition being maintained until the trough pans are supported on the ball frame, the ball frame being thereupon unlocked or released for free reciprocating movement of the shaker troughs.

Yet another object comprehends the provision

2

of a simple latch for a ball frame which holds the frame in a stable condition for transport or handling but which will automatically release the shaker trough pans as soon as they are supported on the frame so that the pans may freely reciprocate on the support.

Other objects of the invention will be apparent from a study of the description herein taken together with the drawings which illustrate a preferred embodiment which the invention may assume in practice. While the invention is described in terms of a preferred embodiment thereof, its scope is not intended to be limited by the embodiment shown nor otherwise than by the claims appended.

In the drawings:

Figure 1 is a side elevation view of a portion of a shaker conveyor system showing the present invention;

Figure 2 is a similar side elevation view, but showing a pair of shaker pan troughs in position;

Figure 3 is an end view of Figure 1, and showing certain details in vertical section;

Figure 4 is a plan view of Figure 1;

Figure 5 is a horizontal section taken along the line 5—5 of Figure 2, looking in the direction of the arrows;

Figure 6 is an enlarged isometric view of a portion of the ball frame shown in Figures 1, 2 and 4, inclusive; and

Figure 7 is an enlarged detail view of a pivot for the latch shown in Figures 1 to 6, inclusive.

Referring now to the drawings, there is shown a pair of shaker conveyor trough pans 11 and 12 connected in abutting relationship. Each trough pan is of the usual construction and has a flat bottom 13 and outwardly inclined flared sides 14, the end of the trough pan 11 being provided with a stiffener 16, and the trough pan 12 being provided with a stiffener 17, the placement of the stiffeners being such that the stiffener 16 is in underlapping relationship with the trough pan 12.

The troughs 11 and 12 are supported for reciprocating movement on a ball frame indicated generally at 18, such a ball frame 18 consisting of a stationary portion 19 comprising spaced guideways 21 which are welded at the ends thereof to angle members 22 which in turn are welded to cross members or ties 23. The ends of the ties 23 or cross members 23 may preferably be provided with feet 24 having cleats 26 which are adapted to grip a mine floor. As shown in Figures 3 and 4 the cross members 23 may be firmly held to the mine floor by means of jacks or struts 27 which extend upwardly and bear against the mine roof,

and which fit into depressions 25 in the ends of the ties 23.

The spaced guideways 21 of the stationary frame portion 19 cooperate with similarly spaced guideways 23 of a movable frame portion 29, the guideways 23 being held together along their length by means of a plate 31 and gusset plates 32 welded thereto and also welded together, see particularly Figures 4 and 6. The guideways 21 and 23 have rolling therein a plurality of balls 33 in a manner well known to the art.

The movable frame portion 29 is adapted to support the shaker trough pans 11 and 12 by means of a pair of standards 34 situate at each end of a stiffener channel 36 which is welded to the plate 31. The standards 34 cooperate with a pair of ears 37 which are pin connected thereto as at 38, and the ears 37 are each provided with an aperture 39 to receive a boss or pin 41 formed in a connector member 42 secured to the end of the trough pan 11 on each side thereof in any convenient manner, as by welding, see Figures 2 and 5. The shaker pan 12 is also provided with a connector member 43 on each side thereof which has a recess 44 milled in the end thereof contiguous to the ear 37 so that the shaker pan 12 may be rested upon the end of the pin or boss 41 which protrudes through the aperture 39 formed in the ear 37.

The pans 11 and 12, which as described thus far are adapted to be supported on the movable frame portion 29, are also adapted to be connected together by means of a C-clamp 46, see particularly Figure 5, having spherical surface 47 adapted to cooperate with a similar spherical surface formed on the connector member 43 to provide a hook end for the C-clamp 46 which is also provided with a similar spherical surface 49 cooperating with a spherical surface 51 in the connector member 42, as more fully described in Hagenbook Patent No. 2,344,300, Shaker Conveyor Trough Connecting Means, issued March 14, 1944. The C-clamp 46 is adapted detachably to hold the shaker pans 11 and 12 together, and to this end for such attachment the C-clamp 46 has cooperating therewith a T-headed bolt 52 which passes through an aperture 53 formed in the connector 42, see also Figure 1, but arms of the T being adapted to span the aperture 53. The clamp 46 is adapted to draw the connector members 42 and 43 firmly together by means of a coil spring 54 surrounding the bolt 52 and a nut 56 in a manner well known to the art.

As has been pointed out hereinabove, the ball frames of the prior art have been characterized by instability when being transported from one place to another, that is to say, the movable frame portion 29 was capable of unrestrained movement with respect to the stationary frame portion 19 in such transport. Further, the lining up of the shaker pan troughs with the ball frame was a difficult process because of such instability even after the frame was placed on the mine floor. Thus, difficulty was encountered in lining up the pins 41 with the apertures 39, and as has been pointed out such instability was oftentimes accompanied by time and labor consuming accidents to those attempting to place a conveyor system into operation. In order to obviate the difficulties heretofore encountered, means are provided to maintain the movable frame portion 29 in fixed relationship to the stationary frame portion 19, preferably until both shaker pans 11 and 12 are supported upon the movable frame portion 29. To this end the movable frame portion

29 is provided with a latch indicated generally by the ordinal 57 which is pivotally connected to the movable frame portion 29 of the ball frame 18, see Figure 7, a pin 58 being provided for such pivoted connections which passes through legs 59 of a substantially U-shaped flange welded to the plate 31. The latch 57 also consists of a member 61 which is adapted to straddle the tie 23, as shown in Figure 6, spring means being provided to urge the latch 57 to a position whereby the member 61 engages the tie 23 at times when the ball frame 18 is being transported from one place to another, or when shaker pan 11 only is being supported by the ball frame 18. The spring means for maintaining the latch 57 in position as shown in Figure 6 consists of a leaf spring 62, one end of which is inserted into an opening 63 formed in one flange of the stiffener channel 36, see also Figures 1, 2 and 4, one end of the spring abutting the interior of the stiffener channel 36 as at 64, the other end of the spring 62 being notched as at 66 to straddle the latch 57, the bottom of the notch 66 being adapted to fit into a notch 67 formed in the latch 57. The latch 57 also includes an operator or member 68 adapted to be engaged by the stiffener member 17 of the trough pan 12 when the trough pan 12 is supported upon the pin 41 at the connector member 43. In so doing the latch 57 is rocked about the pivot 58 thus disengaging the member 61 from the tie 23, thereby causing the trough pan sections 11 and 12 to be capable of free reciprocating movement with the movable ball frame portion 29. In moving to the position shown in Figure 2 by the placing of the trough pan 12 upon the movable frame support 29, the leaf spring 62 is moved to the position shown in Figure 2, thereby imposing a strain thereon, and it will be apparent that upon the removal of the trough 12 from its support at the pin 38 that the latch 57 will be immediately caused to be rocked in a counterclockwise direction as seen in Figure 2 so that the member 61 once more straddles the tie 23 to maintain the ball frame 18 in locked condition.

It will be seen from the foregoing description that by the present invention a ball frame of a shaker conveyor system may be instantly placed in condition for being readily transported, and upon being subsequently relocated being placed in condition for free reciprocating movement of the movable portion of the ball frame as soon as the shaker troughs are put into place. It should be noted here that when the expression "ball frame" is used in this specification such expression is intended to embrace any kind of a supporting frame for the shaker trough sections of a shaker conveyor system where such support frame comprises a stationary portion and a movable frame portion adapted to support the shaker conveyor trough pans for reciprocating movement with respect to such stationary portion.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a ball frame for supporting trough pans of a shaker conveyor system, a stationary frame portion, a moving frame portion supporting said

trough pans for reciprocating movement, and means for locking said moving frame portion in a fixed position with respect to said stationary frame portion except when said trough pans are supported on said moving frame portion, said moving frame and stationary frame portions being characterized by being held together for portability as a unit when not supporting said trough pans and being incapable of relative reciprocatory movement during such portability.

2. In a ball frame for supporting trough pans of a shaker conveyor system, a stationary frame portion, a moving frame portion supporting said trough pans for reciprocating movement, and latch means for locking said moving frame portion in a fixed position with respect to said stationary frame portion except when said trough pans are supported on said moving frame portion, said moving frame and stationary frame portions being characterized by being held together for portability as a unit when not supporting said trough pans and being incapable of relative reciprocatory movement during such portability.

3. In a ball frame for supporting trough pans of a shaker conveyor system, a stationary frame portion, a moving frame portion mounted on said stationary frame portion and supporting said trough pans for reciprocating movement, and means for locking said moving frame portion in a fixed position with respect to said stationary frame portion except when said trough pans are supported on said moving frame portion, said moving frame and stationary frame portions being characterized by being held together for portability as a unit when not supporting said trough pans and being incapable of relative reciprocatory movement during such portability.

4. In a ball frame for supporting trough pans of a shaker conveyor system, a stationary frame portion, a moving frame portion mounted on said stationary frame portion and supporting said trough pans for reciprocating movement, and latch means for locking said moving frame portion in a fixed position with respect to said stationary frame portion except when said trough pans are supported on said moving frame portion, said moving frame and stationary frame portions being characterized by being held together for portability as a unit when not supporting said trough pans and being incapable of relative reciprocatory movement during such portability.

5. In a ball frame for supporting trough pans of a shaker conveyor system, a stationary frame portion, a moving frame portion mounted on said stationary frame portion and supporting said trough pans for reciprocating movement, and latch means for locking said stationary frame portion and said moving frame portion against movement relative to each other comprising a locking member engaging said stationary frame portion and a second member adapted to be engaged by a trough pan supported on said moving frame portion, said last-named member being operable to release said locking member for movement of said stationary frame portion and said moving frame portion relative to each other.

6. In a ball frame for supporting trough pans of a shaker conveyor system, a stationary frame portion, a moving frame portion mounted on said stationary frame portion and supporting said trough pans for reciprocating movement, and latch means for locking said stationary frame portion and said moving frame portion against movement relative to each other, said latch means being pivotally connected to said moving frame

portion and including a locking member engageable with said stationary frame portion, and a second member adapted to be engaged by a trough pan supported on said moving frame portion to rock said locking member about said pivoted connection to release said moving frame portion for movement relative to said stationary frame portion.

7. In a ball frame for supporting trough pans of a shaker conveyor system, a stationary frame portion, a moving frame portion mounted on said stationary frame portion and supporting said trough pans for reciprocating movement, latch means for locking said stationary frame portion and said moving frame portion against movement relative to each other comprising a member engaging said stationary frame portion, and a second member adapted to be engaged by a trough pan supported on said moving frame portion, said last-named member being operable to release said first-named member for movement of said stationary frame portion and said moving frame portion relative to each other, and resilient means for urging said latch means to a position whereby said moving frame portion and said stationary frame portion are locked against movement with respect to each other upon removal of a trough pan from support by said moving frame portion.

8. In a ball frame for supporting trough pans of a shaker conveyor system, a stationary frame portion, a moving frame portion mounted on said stationary frame portion and supporting said trough pans for reciprocating movement, latch means for locking said stationary frame portion and said moving frame portion against movement relative to each other, said latch means having a pivoted connection with said moving portion and including a locking member engaging said stationary frame portion, and a second member adapted to be engaged by a trough pan supported on said moving frame portion to rock said locking member about said pivoted connection to release said moving frame portion for movement relative to said stationary frame portion, and resilient means for urging said latch means to a position whereby said moving frame portion and said stationary frame portion are locked against movement with respect to each other upon removal of a trough pan from support by said moving frame portion.

9. In a ball frame for supporting trough pans of a shaker conveyor system, a stationary frame portion comprising spaced guideways and a tie connecting said spaced guideways, a moving frame portion having correspondingly spaced guideways adapted to cooperate with the spaced guideways of said stationary frame portion, and a latch having a pivoted connection with said moving frame portion and provided with a catch adapted to engage said tie, said latch being provided with a latch operator adapted to rock the latch about said pivoted connection when a trough pan is mounted on said movable frame portion whereby said moving frame portion may move relatively to said stationary frame portion.

10. In a ball frame for supporting trough pans of a shaker conveyor system, a stationary frame portion comprising spaced guideways and a tie connecting said spaced guideways, a moving frame portion having correspondingly spaced guideways adapted to cooperate with the spaced guideways of said stationary frame portion, and a latch having a pivoted connection with said moving frame portion and provided with a catch adapted to engage said tie, said latch being pro-

vided with a latch operator adapted to rock the latch about said pivoted connection when a trough pan is mounted on said movable frame portion whereby said moving frame portion may move relatively to said stationary frame portion, and resilient means for rocking said latch in a direction to lock the moving frame portion against movement with respect to said stationary frame portion upon removal of a trough pan from said moving frame portion.

11. The combination with a mechanical shaker conveyor system of a ball frame for supporting shaker trough pans for reciprocating movement, the ball frame comprising a stationary frame portion and a moving frame portion adapted to move with respect to said stationary frame portion, and means for locking said moving frame portion in a fixed position with respect to said stationary frame portion except when said shaker trough pans are supported by said ball frame, said moving frame and stationary frame portions being characterized by being held together for portability as a unit when not supporting said trough pans and being incapable of relative reciprocatory movement during such portability.

12. The combination with a mechanical shaker conveyor system of a ball frame for supporting shaker trough pans for reciprocating movement, the ball frame comprising a stationary frame portion and a moving frame portion adapted to move with respect to said stationary frame portion, and latch means for locking said movable frame portion against movement with respect to said stationary frame portion comprising a member engaging said stationary frame portion and a second member adapted to be engaged by a trough pan supported by said ball frame, said latch means being adapted to release said movable frame portion for movement with respect to said stationary frame portion when a trough pan is supported by said ball frame.

13. The combination with a mechanical shaker conveyor system of a ball frame for supporting shaker trough pans for reciprocating movement, the ball frame comprising a stationary frame portion and a moving frame portion adapted to move with respect to said stationary frame portion, and latch means for locking said movable frame portion against movement with respect to said stationary frame portion comprising a member engaging said stationary frame portion and a second member adapted to be engaged by a trough pan supported by said ball frame, said latch means being adapted to release said movable frame portion for movement with respect to said stationary frame portion when a trough pan is supported by said ball frame, and resilient means for urging said first-named member to engage said stationary frame portion upon removal of a trough pan to prevent movement of said movable frame portion with respect to said stationary frame portion.

14. The combination with a mechanical shaker conveyor system of a ball frame for supporting shaker trough pans for reciprocating movement, the ball frame comprising a stationary frame portion having spaced guideways thereon, a tie for maintaining said guideways in spaced relationship, a movable frame portion having spaced guideways adapted to cooperate with the guideways of said stationary frame portion, and a latch

10 having a pivoted connection to said moving frame portion and provided with a catch adapted to engage said tie, said latch including a latch operator adapted to rock the latch about said pivoted connection when a trough pan is mounted on said movable frame portion, whereby the movable frame portion is freed for reciprocating movement.

15. The combination with a mechanical shaker conveyor system of a ball frame for supporting shaker trough pans provided with connecting means for unitary reciprocating movement, the ball frame comprising a stationary frame portion and a moving frame portion adapted to move with respect to said stationary frame portion, and

20 means for locking said moving frame portion in a fixed position with respect to said stationary frame portion except when said shaker trough pans are supported by said ball frame, said moving frame and stationary frame portions being characterized by being held together for portability as a unit when not supporting said trough pans and being incapable of relative reciprocatory movement during such portability.

25 16. The combination with a mechanical shaker conveyor system of a ball frame for supporting shaker trough pans having connecting means for unitary reciprocating movement, the ball frame comprising a stationary frame portion and a moving frame portion adapted to move with respect to said stationary frame portion, and latch means for locking said movable frame portion against movement with respect to said stationary frame portion comprising a member engaging said stationary frame portion and a second member 30 adapted to be engaged by a trough pan supported by said ball frame, said latch means being adapted to release said movable frame portion for movement with respect to said stationary frame portion when a trough pan is supported by said ball frame.
